5 Claims. (Cl. 139—170.6)

1

The invention relates to a device for the separation of the wefts in multiple box looms.

It is the principal object of the invention to overcome the difficulty arising in such looms which consists in that the wefts running from the edge of the fabric towards the various cells of the shuttle box often get slack owing to the up-and down-movement of the shuttle box, and are then caught by the wefts of that shuttle, which is being picked towards the other side of the loom, and are carried more or less deeply into the shed. Thereby so-called "runners-in" are formed which have to be sewn-out, a work which is often very difficult.

It is another object of the invention to provide a device capable of braking and of holding-fast the weft of the shuttle, which has run into a cell of the shuttle box, while the said shuttle box is being lowered or raised for the next pick, and which is capable of preventing any undesirable slackening of such weft during such movement of the shuttle box.

Other objects of the invention will appear from the description of an embodiment thereof later in the specification.

According to a main feature of the invention, a device for the separation of the wefts in multiple box looms comprises in combination: a slay, a shuttle box having a plurality of cells on top of one another and slidably arranged on the said slay for bringing any one of the said cells into operative position, shuttles, each carrying a weft and arranged for being shot into and picked out of one of the said cells in the operative position thereof, and two braking- and holding devices for the stretches of the wefts running from the shuttles contained in the said cells towards the edge of the fabric, the said slay being so arranged as to introduce by its movement the weft from the shuttle having arrived in its cell at the end of the preceding pick into one of the said braking- and holding devices when the said shuttle box is being lowered, and into the other one of the said braking- and holding devices when the said shuttle box is being raised preparatory to the next subsequent pick.

In order that the invention may be better understood and readily carried into effect, an embodiment thereof will now be described by way of example with reference to the accompanying drawings. And while I illustrate and describe a useful embodiment of my invention, I wish it to be understood that I do not desire to be limited to the exact details of construction shown and described, for obvious modifica-

2

tions will occur to a person skilled in the art. In the drawings:

Fig. 1 shows an elevation of one end of the slay of a multiple box loom having a shuttle box with five cells and a device for the separation of the wefts as seen from the side of the fabric, partly in section.

Fig. 2 shows a section along the line A—A of Fig. 1, the rearmost position of the slay being shown in full lines, and the foremost position of the slay in dotted lines.

Fig. 3 is a plan view to Fig. 2, and Fig. 4 is a plan view corresponding to Fig. 3 of the slay in its rearmost position after the arrival of a shuttle in a cell of the shuttle box.

The slay sword of a multiple box loom (which is otherwise not shown) is denoted 1. At the end of this slay sword 1 there is a shuttle box 3 having five cells 3a, 3b, 3c, 3d, 3e guided in a guide 2 so as to be shiftable up and down. In the case represented, in each of the cells 3a, 3c and 3e there is a shuttle 4a, 4c, 4e, respectively, the wefts of which are denoted 5a, 5c and 5e, whereas the cells 3b and 3d are shown empty for the sake of simplicity. On the guide 2 of the shuttle box 3 there is attached a so called partition plate 6, and on the slay sword 1 there is attached a slay plate 7. The partition plate 6 and the slay plate 7, the outer edges 6' and 7' of which run obliquely towards the fabric, are connected with one another by a bolt 8. On the slay plate 7 there is moreover arranged an axle 9 on which a brush carrier 10 with two tufts of bristles 11 and 11' is rotatably and adjustably arranged. The tufts of bristles 11 and 11' are positioned obliquely to the directions of the warps and of the wefts, and, pointing towards the edge of the warp and towards the side of the fabric, they resiliently abut against the partition plate 6 and the slay plate 7, respectively. The slay plate 7 and the brush 11 constitute a braking and holding device, and the partition plate 6 and the brush 11' constitute another braking and holding device for the wefts. The intermediate bottoms 12a, 12b, 12d and 12e separating the cells 3a from 3b, 3b from 3c, 3c from 3d, and 3d from 3e, each have a recess 13a, 13b, 13d and 13e, respectively, on their front i. e. on the side pointing towards the fabric.

The shuttle runs into the associated cell of the shuttle box 3 when the slay sword 1 is approximately in its rearmost position. In Fig. 3 this position is shown in full lines, the cell 3c being in the operative position wherein the shuttle 4c has just run into the same. After the arrival

of the shuttle 4c in the cell 3c of the shuttle box 3, the following cases may arise:

(1) in the subsequent pick the shuttle 4c is again to be shot, towards the other side of the loom;

(2) in the subsequent pick the shuttle 4e is to be shot towards the other side of the loom, i. e. the shuttle box 3 is to be moved upward;

(3) in the subsequent pick the shuttle 4a is to be shot towards the other side of the loom, i. e. the shuttle box 3 is to be lowered.

In the first case, the weft 5c need not be held fast, since it is to be carried at once into the shed again. In the second case, the shuttle box 3 is shifted upward immediately after the arrival of the shuttle 4c in its cell 3c, in such a manner that its cell 3e containing the shuttle 4e arrives in the operative position. In the position of the slay sword 1 as shown in Fig. 3 in dotted lines this shifting of the shuttle box 3 is already accomplished. The weft 5c is thereby drawn into the recess 13d of the intermediate bottom 12d and is bent around its base edge. Thereby the weft 5c is prevented from sliding off towards the centre of the path of the slay. In the subsequent return movement of the slay sword 1 into the position shown in Fig. 3 in full lines, the weft 5c slides along the oblique edge 6' of the partition plate 6 and is pulled under the tuft of bristles 11 by the downward pull. As soon as this is effected, the weft 5c can get slack no more in the range of the width of the sheet of the loom, since it is held fast by the bristles of the brush 11, and it can not slide off towards the sheet either, since this is prevented by the bristles of the brush 11 which are obliquely directed away from the sheet. At the subsequently effected lowering of the shuttle box 3, the wefts 5a and 5b running towards the upper cells 3a and 3b get somewhat slack, though, but merely on the stretch between the tuft of bristles 11' and the recess 13a or 13b of the intermediate bottoms 12a and 12b, respectively, so that in no case they can be caught and carried with by the shuttle entering the cell.

Correspondingly, the same happens, when, according to the third case, the shuttle box 3 is not raised but is lowered, so that its cell 3a containing the shuttle 4a gets into the operative position; the only difference is that the weft 5c slides subsequently along the oblique edge 7' of the slay plate 7 and gets under the bristles of the tuft 11.

When now the shuttle which is actually in the operative position, i. e. either 4e or 4a, is picked out of its cell towards the other side of the loom, its weft 5c or 5a, respectively, is slung around the bristles of the tuft 11 or 11', respectively, and is pulled out from underneath the tuft of bristles 11 or 11', respectively, because the bristles of the tuft 11 or 11', respectively, are directed towards the edge of the warp and do not offer any resistance to that movement.

What I claim as my invention and desire to secure by Letters Patent, is:

1. A device for the separation of the wefts in multiple box looms for weaving a fabric, comprising in combination, a slay; a shuttle box having a plurality of cells located on top of one another slidably arranged on said slay for bringing any one of said cells into operative position; a plurality of shuttles, each shuttle carrying a weft and arranged for being shot into and picked out of said cells in the operative position thereof, and two braking and holding devices located

on said slay and resiliently engaging the portions of the wefts running from the shuttles contained in said cells toward the edge of the fabric, one of said two braking and holding devices including a slay plate attached to said slay below the path of the shuttles and a brush resiliently abutting with a tuft of bristles from above against said slay plate, and the other of said two holding devices including a partition plate attached to said slay above the path of the shuttles and a brush resiliently abutting with a tuft of bristles from below against said partition plate, both said tufts of bristles being positioned obliquely to the directions of the warps and of the wefts of the fabric, respectively, and pointing towards the fabric, said slay being arranged for introducing by its movement the weft from the shuttle having arrived in the corresponding cell of the preceding pick into one of said braking devices when said shuttle box is being lowered, and into the other one of said two braking and holding devices when said shuttle box is being raised.

2. A device for the separation of the wefts in multiple box looms for weaving a fabric, comprising in combination, a slay; a shuttle box slidably arranged on said slay and including a plurality of parallel spaced bottom walls defining a plurality of cells located on top of one another, each of said bottom walls having a recess in the edge thereof adjacent to said slay and guiding the weft of a shuttle located in the corresponding cell during shifting of said shuttle box for bringing any one of said cells into an operative position; a plurality of shuttles, each shuttle carrying a weft and arranged for being shot into and picked out of said cells in the operative position thereof, and two braking and holding devices located on said slay and resiliently engaging the portions of the wefts running from the shuttles contained in said cells toward the edge of the fabric, one of said two braking and holding devices including a slay plate attached to said slay below the path of the shuttles and a brush resiliently abutting with a tuft of bristles from above against said slay plate, and the other of said two holding devices including a partition plate attached to said slay above the path of the shuttles and a brush resiliently abutting with a tuft of bristles from below against said partition plate, both said tufts of bristles being positioned obliquely to the directions of the warps and of the wefts of the fabric, respectively, and pointing towards the fabric, said slay being arranged for introducing by its movement the weft from the shuttle having arrived in the corresponding cell of the preceding pick into one of said braking devices when said shuttle box is being lowered, and into the other one of said two braking and holding devices when said shuttle box is being raised.

3. A device for the separation of the wefts in multiple box looms for weaving a fabric, comprising in combination, a slay; a shuttle box slidably arranged on said slay and including a plurality of parallel spaced bottom walls defining a plurality of cells located on top of one another, each of said bottom walls having a recess in the edge thereof adjacent to said slay and guiding the weft of a shuttle located in the corresponding cell during shifting of said shuttle box for bringing any one of said cells into an operative position; a plurality of shuttles, each carrying a weft and arranged for being shot into and picked out of one of the said cells in the operative position thereof, and two braking and holding devices mount-

ed on said slay for the stretches of the wefts running from the shuttles contained in the said cells towards the edge of the fabric, the said slay being arranged for introducing by its movement the weft from the shuttle having arrived in its cell at the end of the preceding pick into one of the said braking and holding devices when the said shuttle box is being lowered, and into the other one of the said braking and holding devices when the said shuttle box is being raised, preparatory to 10 the next subsequent pick.

4. A device for the separation of the wefts in multiple box looms as claimed in claim 1 comprising a common brush holder rotatably and adjustably arranged on the said slay plate and 15 adapted to carry both the said tufts of bristles.

5. A device for the separation of the wefts in multiple box looms as claimed in claim 1 wherein the said slay plate and the said partition plate each comprises on their outer side an edge portion directed obliquely towards the fabric and serving for guiding the wefts into the respective braking and holding device.
